(57) **CLAIM**

The ornamental design for a lawn rake, as shown and described.

DESCRIPTION

FIG. 1 is a front perspective view of a lawn rake, showing my new design;

FIG. 2 is a rear perspective view thereof;

FIG. 3 is a rear view thereof;

FIG. 4 is a front view thereof;

FIG. 5 is right side view thereof;

FIG. 6 is a left side view thereof;

FIG. 7 is a bottom view thereof;

FIG. 8 is a top view thereof;

FIG. 9 is a front perspective view showing the lawn rake in a use state;

FIG. 10 is a front perspective view showing the lawn rake in a use state; and,

FIG. 11 is an enlarged detail view of area 11 in FIG. 1. The broken lines in the drawings illustrate the portions of the lawn rake, which form no part of the claimed design. The dash-dot-dash broken lines encircling the enlarged views are for annotative purposes only and form no part of the claim thereof.
